UNITED STATES PATENT OFFICE

2,575,384

THROTTLE CONTROL FOR MOTOR VEHICLE ENGINES

Erwin C. Horton, Hamburg, N. Y., assignor to
Trico Products Corporation, Buffalo, N. Y.

Application July 1, 1949, Serial No. 102,597

2 Claims. (Cl. 123—103)

1

This invention relates to motor vehicle engines of the internal combustion type which utilizes the well known carburetor for providing the desired combustible mixture. Such mixture passes through the intake manifold to the combustion chambers, its passage being controlled by a butterfly valve disposed in the manifold and often referred to as the engine throttle.

For engine idling, the throttle is set or given a definite adjustment called its closed position and to which position it returns when releasing the accelerator pedal or otherwise fully throttling the engine. While this idling position of the throttle is correct and proper for normal operation, yet under certain conditions a different adjustment should be made to avoid the "stalling" of the engine. Thus, when starting a cold engine, or when braking the vehicle and through the inertia of the fuel in the carburetor, or otherwise, a sudden enrichment of the combustible mixture is caused sufficient to stall the engine, if the throttle is opened a slight degree, or in other words the idling position is temporarily "advanced" toward engine acceleration, the starting of the cold engine will be facilitated and the stalling of the idling engine will be avoided.

The present invention has for its object to provide a control for motor vehicle engines which will automatically prevent the decelerating of a dying engine by immediately opening the intake passage as the engine requires it and thereafter retarding the closing action to insure the engine acceleration over a definite period.

This invention also has for its object the automatic adjustment of the extent of the opening past the throttle valve in accordance with the value of the suction or low pressure conditions in the intake manifold whereby the throttle valve is given at all times the extent of opening necessary to insure an adequate amount of the explosive mixture of the engine to maintain operation thereof and to compensate for variations in the pressure condition pertaining in the intake manifold.

Further the invention has for its object to provide a motor vehicle engine which will be free from stalling and one which will quickly start upon the initial turning over of the engine.

In the drawings:

Fig. 1 is a fragmentary elevation of a motor vehicle internal combustion engine embodying the present invention; and

Fig. 2 is a sectional view of one embodiment of the automatic throttle control of the invention herein.

2

Referring more particularly to the accompanying drawings the numeral 1 designates the internal combustion engine of a motor vehicle, having an intake manifold 2 with a throttle valve 3, the idling position of which is determined by the adjustable stop 4. The throttle 3 is depicted as having a bell crank lever 5 fixed to its shaft 6 and provided with a shoulder 7 with which the stop 4 cooperates to determine the idling position. The bell crank has a link connection 8 with an accelerator or other manual control (not shown) by which the throttle may be manually opened and closed for proper vehicular manipulation and travel. These parts are herein shown as illustrative only, no emphasis being placed on the structural features of these well known parts.

While the manually set idling position of the throttle, as determined by the stop 4, is proper for a portion of the vehicular and engine operations, still, there are times and conditions as previously mentioned, when it is desired to advance or open the throttle slightly beyond the normal idling "set." It is known that during the life of a motor vehicle engine that the initial set of the throttle valve becomes changed due to vibration and wear of parts and also that the initial idling throttle position becomes ineffective or inadequate to maintain the feed of a sufficient amount of fuel to the engine to maintain it in operation due, among other things, to wear of the piston rings and cylinder, to an accumulation of carbon deposits in the cylinders, resulting in a less efficient vacuum condition in the intake manifold, thus resulting in the drawing of a smaller volume of the explosive mixture past the throttle valve in its initial adjustment for idling operation of the engine. Frequently, the engine will stall when bringing the vehicle to rest at a traffic signal, and if the driver is not alert or acquainted with the fact that his engine has died he will delay the traffic when the signals change to "proceed." Further, with the advent of the "free wheeling," the engine is permitted to idle while the vehicle is traveling at a faster speed. Consequently, when the vehicle is braked or the momentum is checked so as to cause a sudden enrichment of the combustible mixture, not infrequently due to the inertia of the liquid fuel in the system, the engine will stall. Such stalling might be avoided if the motorist would tramp his throttle in time to open the intake manifold. Also if the stop 4 was advanced a little such stalling might be avoided, but such advancing of the stop would cause the engine to race unnecessarily at normal idling.

In accordance with the present invention means are provided to automatically increase the volumetric intake of the combustible mixture by the engine, to automatically advance the throttle, or open the same, so as to slightly accelerate the engine; and to prolong the period of open throttle state sufficiently to insure the desired engine acceleration.

Thus, a chamber 9, having communication with the intake manifold at the engine side of the throttle, as by a conduit 10, has a movable wall 11 which is resiliently urged in one direction of movement and adapted to be moved in the opposite direction by suction or a partial vacuum in the chamber. If the movable wall, herein depicted as a diaphragm, is not inherently resilient, a spring 12 may be provided for producing the resilient urge, such urge being utilized for moving the throttle to its advance setting to thereby accelerate the engine back to its normal idling, which is determined by the stop 4. The spring 12 is preferably disposed within the chamber, the same acting to advance the throttle. The chamber may be conveniently arranged with respect to the manifold or carburetor, and its movable wall 11 may be connected to the throttle as by means of a rod or stem 13. Because a play connection is desired the rod has a shoulder 13' upon which an arm of the bell crank 5 rests so that operation of the latter may be had independently of the movable wall 11. The movement of the wall under the action of the spring 12, and consequently the extent of advance given the throttle, may be varied by an adjustable stop 14. This stop is herein depicted in the form of a sleeve threaded in a spider or bracket 15 and serves to guide the stem 13 in its reciprocations. The movement of the wall 11 in response to the manifold suction, may be governed by adjustable tensioning means for the spring 12. Thus, by adjusting the screw 16 in or out, the cup 17 carried thereby and supporting the lower end of the spring will correspondingly increase or decrease the spring tension so that the movable wall will respond to more or less manifold suction.

As the engine begins to die, the manifold suction will decrease and when the automatic throttling auxiliary or accelerator functions through the spring action of the wall 11 to open the intake passage the engine becomes slightly accelerated and restored to the idling speed.

To insure this acceleration a dashpot 18 is provided to retard the response of the wall 11 to the restored idling suction. The dashpot illustrated, by way of example, comprises a chamber 19 and a piston 20, the latter being connected to the stem 13 by an integral extension 21 of the latter. A one-way check valve 22 freely opens a transfer port 23 against the urge of a spring 24 when the spring 12 functions but closes upon reverse movement of the piston 20 to retard the movement of wall 11 when the idling suction is restored by the engine acceleration. This prolongs the

interval during which the throttle remains partly open so as to give the engine a longer period of acceleration and thereby insure the maintenance of proper engine idling operation. During the retarded return movement, when the ball valve 22 is seated, there will be a predetermined air leakage about the periphery of the piston.

In operation, if the engine is at rest the spring 12 will be acting through the movable wall and its stem 13 to hold the throttle in its advance idling position. Thus, the throttle will be opened a certain degree sufficient to facilitate the starting of the engine. Immediately upon starting and the formation of a vacuous condition in the intake manifold, the movable wall will be moved away from the throttle and the latter will be returned to its normal throttling position as retarded by the dashpot, such return being effected by means of the usual throttle spring 25. Should the cold engine begin to die or slow down sufficiently to reduce the suction influence on the movable wall the spring 12 will again function to advance the throttle.

What is claimed is:

1. A carburetor throttle valve arranged in a fuel intake means responsive to the intake suction normally for holding the valve closed during engine idling, means normally counteracted by said first means and operable to open the throttle valve when the engine tends to stall, and a fluid dashpot means acting to retard the closing of the valve following its operation by said second means.

2. Engine fuel intake means, a carburetor throttle valve, pressure differential operated means controlled by the difference in pressure between the interior and exterior of the fuel intake means for opening the throttle valve if the engine tends to stall while idling, said pressure differential operated means comprising mechanism for moving the throttle valve to a partially open position said movement acting independently of the conventional throttle opening means and intake suction responsive means for over-coming said mechanism, and a dashpot device mechanically connected to the suction responsive means for delaying its operation and acting therethrough to retard the closing of the throttle valve.
